UNITED STATES PATENT OFFICE

1,988,804

ADJUSTABLE STANDING BOOT JACK

Fred P. Meyer, Seattle, Wash.

Application April 20, 1934, Serial No. 721,479

20 Claims. (Cl. 132—5)

The invention relates to boot-jacks.

Principal objects of the invention are:

To provide a boot-jack comprising mechanical devices for gripping the boot, standing erect;

5 By means of which the foot may be withdrawn from the boot quickly, conveniently, and without appreciable effort, by the wearer merely raising his leg;

To provide a boot-jack which may quickly and conveniently be adjusted for use with boots of different sizes;

Which will present a neat appearance.

Which will be simple in construction, strong, durable, and relatively inexpensive to manufacture and maintain; and

To provide a boot-jack which may be folded very compactly into a small space, for conveniently packing, carrying and shipping the same.

Other objects of the invention will also appear.

20 To effect the objects thereof, a boot-jack embodying my invention and improvements comprises the various features, and details of construction hereinafter described and claimed.

In the accompanying drawings, in which the 25 invention is fully illustrated,

Fig. 1 is a top plan view of a boot-jack embodying my invention and improvements, when folded;

Fig. 2 is a bottom plan view thereof, also when folded;

Fig. 3 is a sectional side view of the boot-jack, when folded, in a plane indicated by the line 3—3, Fig. 1;

Figures 4 and 5 are enlarged, transverse, sectional end views in a line 4—4, 5—5, of Fig. 1, looking in opposite directions, as indicated, respectively, by the arrows;

Fig. 6 is an enlarged, transverse, sectional end view, in a plane indicated by the line 6—6, Fig. 1;

40 Fig. 7 is a perspective view of the boot-jack extended; and

Figure 8 is an enlarged, fragmentary, detail view.

Describing the invention with reference to the 45 drawings, my improved boot-jack—for purposes of convenient reference, designated as a whole

A—comprises a base section designated as a whole B, comprising a rectangular frame b consisting of said members 1, 1', rigidly connected

50 at their ends by transverse frame members 2, 2'.

For reasons presently apparent, the side frame members 1, 1', are provided with inwardly facing channels 3 which, as shown, extend the entire length thereof. For convenience and economy

55 the frame b is made of metal channel irons—

preferably a continuous channel cut away and bent at its corners to form the side and end members thereof, and abutting or adjacent cut-away corners of said flanges being rigidly connected, as by brazing, welding or other suitable or desired means.

In order to conveniently grasp said base section B, when it is desired to pick up the boot-jack, it is supported in spaced relation to the floor or other surface on which it rests, by short legs 10 or feet 4, which preferably include one secured to each corner of the frame b, and one to each end of a transverse bar 5 secured to the under sides of the side frame members 1, 1', at, approximately, the longitudinal centers thereof. 15

Said base section B, also comprises a platform b' on which the person using the boot-jack stands. As shown, said platform consists of a rectangular piece of board or other suitable relatively light-weight material, secured—as by screws or other suitable means—to the under side of which adjacent its opposite ends, are plates 7, 7', the lateral edges of which, in operation, rests upon the lower flanges of the side frame members 1, 1', so as

20 to be adjustable lengthwise of said base section 25 B, and which comprises means for securing said platform in different adjusted positions on said frame members 1, 1', consisting, as shown, of studs 8 secured in and which project downwards from the bottom of the rear plate 7' and are interchangeable in series of holes 9 formed in the bottom flanges of said side frame members, as

30 shown, see Figs. 2, 5 and 8.

35 As shown, the board 6 is proportioned to fit 1, 1', between the side bars or members 1, 1', of the frame b with only slight clearance, and the studs 8 are of such length that the distance between their outer ends and the plane of the top side of the plate 7' is sufficiently less than the width of the channels in the side frame members 40 1, 1', to permit raising movement thereof to effect engagement and disengagement of said studs 8 with and from the holes 9 in the bottom flanges of said frame members.

45 In use, the front plate 7 will sustain most of the weight of a person using the boot-jack, and, for that reason, its dimension lengthwise of the frame members 1, 1', is appreciably greater than that of the rear plate 7', thus rendering said plate 7 correspondingly stronger than the plate 7'. 50

As shown, the board 6 forming the supporting surface of the platform b' is of such thickness that its upper surface will be positioned at a distance above the tops of the side frame members 1, 1', of the base frame b about equal to the

55

width of the web portions of said frame members.

The operative parts of the boot-jack are mounted on the base section B, and comprise a slide member designated as a whole b^2 , which comprises tongues or projections 10 on its lateral edges which are slidably fitted to the channels in the side frame members 1, 1', of the base frame b.

As shown, also, the slide member b^2 also comprises a raised portion 11, the relation preferably being such that its top will be in substantially the same plane as the top of the platform b' . As shown, also, said slide member is reinforced and strengthened by a metal plate 12 secured to its under side, which preferably is of the same width as said slide member and forms the surface thereof which slidably engages the bottom flanges of the side frame members 1, 1', of the base frame b, as explained.

In accordance with the invention, movement is adapted to be imparted to the slide member b^2 towards and from the relatively fixed platform b' , by means of a lever designated as a whole b^3 , one end of which is pivoted to lugs 13 secured to the front transverse frame member 2 of the base frame b adjacent its opposite ends, and which is connected with the slide member b^2 by links 14, which, in the preferable construction shown, are cross-connected adjacent their ends pivoted to the lever b^3 by a bale 15, which will cause said links 14 to turn together.

As shown, the lever b^3 is of substantially the same construction and size, as near as may be, as the base frame b and is pivoted to said base frame in such relation that it may be turned pivotally into contact with said base frame, in which position the marginal edges of said base frame b and lever b^3 will register with each other.

As shown, the links 14, which connect the side members of the lever b^3 with the slide member b^2 are connected directly to the lateral sides of said slide member, as shown, see Figs. 1 and 7, to the raised portion 11 of said slide member b^2 , which is sufficiently narrower than the space between the side members 1, 1', of said lever to permit said links 14 and the connections therefor to enter freely between said side members and the raised portion of said slide member, to permit said lever to be turned pivotally into contact with the base frame b.

As shown, the lever b^3 is identical, both in construction and size, as near as may be, with the base frame b and the foregoing description of said base frame will apply equally to said lever, and, without repetition, similar parts of said lever and base frame are designated by the same reference characters on the drawings.

To prevent spreading of the side members 1, 1', both of the base frame b and of the lever b^3 , said side frame members of both structures, are connected between their ends, by tie-bars applied to their outer sides, when they are folded together,—see Figs. 1, 2 and 7—which may be the bar 5 which connects the side members of the base frame b, and a similar bar, also designated 5, which connects the members of said lever.

In accordance with the invention, my improved boot-jack comprises means rendered operative by movement of the slide member b^2 , motivated by the operating lever b^3 , for gripping a boot worn by a person standing on the platform b' , by jaws formed on said slide member and the platform b' . As shown, said gripping jaws, consist of openings 17, 17', formed respectively, in the proximate ends of the portions of the

platform b' and slide member b^2 , which, respectively, are secured to the upper sides of the metal plates 7 and 12, respectively, and which form supporting surfaces for the heel and toe of a boot while being removed.

As shown, the openings 17, 17', are of substantially the same shape and size and are arranged symmetrically with reference to the longitudinal center line of the base portion of B of the boot-jack and, also, substantially symmetrically with reference to the meeting line thereof, when the proximate ends of said platform and slide member are in contact, said openings being widest at their open ends and the sides thereof converging towards their inner ends at angles of approximately forty-five (45) degrees, but which, within the scope and contemplation of the invention, may vary within considerable limits. In removing a boot, it is inserted into the boot-jack with the heel in engagement with the opening 17 and resting upon the plate 7, and the toe thereof in engagement with the opening 17' in the slide member b^2 and resting on the plate 12 which slidably supports said slide member, and to provide for effectively gripping said boot, the platform b' is made of such thickness that it will engage the counter of the boot, while the sides of the opening 17' comprise lower portions 18 arranged at right angles to the plane of the platform, and upper portions 19, which are under-cut, being preferably bevelled, said lower portion being arranged to contact with the edges of the sole of the boot and to guide it into said opening, as presently described, and the bevelled upper portion being arranged to grip the upper edges of the sole of the boot. In the preferable construction, shown, also, the sides of both openings 17, 17' are faced with strips of relatively hard, smooth material, as vulcanized fiber, which will not roughen the parts of a boot which contact therewith, respectively, and which may readily be removed and renewed, in case they become worn or broken in use.

Preferably and as indicated in the drawings, the top surfaces of the platform b' , the slide member b^2 , and the portions of the plates 7 and 12 exposed at the bottoms of the openings 17, 17', are covered with rubber matting, indicated at 20, thus providing a sure footing for a person using the boot-jack, and which may readily be renewed in case they become worn, whereby the boot-jack will always present a neat and attractive appearance.

As previously explained, the operating lever b^3 is pivoted to the base frame b in such manner and relation that it may be turned pivotally into contact with said base frame b, and in accordance with the invention, the boot-jack A is adapted to be secured in such folded position by means of locking means consisting, as shown, see Fig. 6, of plates 21, slidably mounted on base plates 22 secured in fixed position to the rear end of the platform b' , so that they will throw outwards, and which are provided with slots 23 in their outer ends arranged to embrace and lock together the contacting flanges of the side members 1, 1', of said base frame and lever. Also, said locking means, the base plates 22 of which are secured to the rear end of the platform b' , will secure the studs 8 on the supporting plate 7' for said platform in engagement with the holes 9 in the lower flanges of the channels in the side members 1, 1', of the base frame b, thus securing said platform in relatively fixed position to said platform and lever.

In the preferable construction shown, also, rubber pads or cushions 24 are secured to the side frame members 1 or 1' of the base frame b or lever b³ designed to contact with each other when 5 said lever is turned pivotally into folded position, which will reduce both shock and noise in handling the boot-jack, particularly should said lever contact with said base frame with any considerable force. Said pads or cushions, preferably, will 10 be secured to the lever b³, but may be secured to the base frame, if desired.

As shown, the locking plates 21 are slidably mounted on the base plates 22 secured to the rear end of the platform b' by means of guide grooves, 15 to which the edges of said locking plates are fitted, formed by the turned-over edges of said base plates, in a familiar manner. The locking plates 21 are confined in their bearings on the base plates 22 by studs 25 secured in and which project from the rear end of the platform b', in 20 position to limit withdrawal of said locking plates from their bearings. For convenience in manipulating said locking plates 21, they are provided with holes 26, arranged and proportioned for engagement by the finger of a person using said 25 boot-jack.

While I consider the locking means for securing the base frame b and lever b³ shown and described, as preferable, mechanics familiar with 30 such devices can readily supply other locking means. I do not, therefore, desire to limit myself to the particular locking means shown, but to extend the protection of the patent to any means for the purpose.

Having thus described my improved boot-jack, 35 I will now describe the method of operating the same.

Starting with the boot-jack in folded position, substantially as shown in Figs. 1 to 6, the first operation is to withdraw the locking plates 21 to 40 permit the boot-jack to be extended. Having done this, a person desiring to remove his boots, first turns the lever b³ into the position shown in Fig. 7. If the platform b' is properly adjusted for 45 removing the size of boot worn by said person, he then grasps the free end of the lever b³, steps upon the platform b', and inserts one boot into the space defined by the openings 17, 17' formed in the proximate ends of said platform and the 50 slide member b², with the heel and sole of the boot resting on the supporting plates 7 of the platform, and 12 of said slide member, with his weight, for the most part, carried on the foot and leg resting on the platform b'.

He then exerts a pull on the free end of the 55 lever b³ to advance the slide member b² towards the platform b'—which will first operate to force the bevelled sides of the opening 17' in said slide member into engagement with the sole of the boot, and will then crowd the foot of the boot 60 into the opening 17 in the platform b' to effect contact of the heel portion of the boot—preferably the counter thereof—with the converging sides of said opening. Owing to the great lever-age with which the lever b³ acts, the jaws of 65 the jack may be caused to engage the boot with a grip of almost any desired strength, by the application to said lever of relatively little force.

In case it is found that the position of the 70 platform b' relative to the slide member b², is incorrect, its position can readily be adjusted by raising said platform to disengage the studs 8 thereon from the holes 9 in the bottom flanges of the side members 1, 1', of the base frame b 75 and then move said platform in one direction or

the other, as it may be found necessary to increase or decrease the operative size of the space defined by said openings 17, 17', in said platform and slide members, respectively.

I claim,

1. In a boot-jack, the combination of a base section comprising a supporting frame, a platform, means for mounting said platform on said supporting frame, a slide member, means for slidably mounting said member on said supporting frame, means for imparting relative movement to said slide member and platform towards and from each other, and cooperating jaws on said platform and slide member arranged for gripping a boot supported between them, and rendered operative to grip and release a boot by relative movement of said platform and slide member towards and from each other.

2. The boot-jack specified in claim 1, in which the platform is adjustably mounted on the supporting frame, and which comprises means for securing said platform in relatively fixed position thereto.

3. The boot-jack specified in claim 1, in which the platform is adjustably mounted on the supporting frame, and which comprises means for securing the same in adjusted positions thereto.

4. The boot-jack specified in claim 1, in which the platform is adjustably mounted on the supporting frame, and which comprises means for securing the same in adjusted positions thereto, consisting of a stud secured to said platform which is interchangeable in a series of holes formed in said supporting frame.

5. The boot-jack specified in claim 1, in which the platform is adjustably mounted on the supporting frame, and which comprises means for securing it in adjusted positions thereto, and in which, also, the slide member is slidably mounted on said supporting frame and is movable thereon towards and from said platform, and which comprises means for imparting movement thereto towards and from said platform.

6. The boot-jack specified in claim 1, in which the platform is adjustably mounted on the supporting frame, and which comprises means for securing it in adjusted positions thereto, and in which, also, the slide member is slidably mounted on said supporting frame and is movable towards and from said platform, and which comprises means operable by a person standing on the platform of the boot-jack, for imparting movement to said slide member towards and from said platform to effect engagement of the jaws thereon, respectively, with a boot supported between said slide member and the platform, and to release the same.

7. The boot-jack specified in claim 1, in which the platform is adjustably mounted on the supporting frame, and which comprises means for securing it in adjusted positions thereto, and in which, also, the slide member is slidably mounted on said supporting frame and is movable towards and from said platform, and which comprises means operable by a person standing on the platform of the boot-jack, for imparting movement to said slide member towards and from said platform to effect engagement of the jaws thereon, respectively, with a boot supported between said slide member and the platform, and to release the same, and consisting of a lever pivoted to said supporting frame and a link or links which connect said lever with said slide member.

8. The boot-jack specified in claim 1, in which

the platform is adjustably mounted on the supporting frame, and which comprises means for securing it in adjusted position thereto, and in which, also, the slide member is slidably mounted on said supporting frame and is movable towards and from said platform, and which comprises means operable by a person standing on the platform of the boot-jack for imparting movement to said slide member towards and from said platform to effect engagement of the jaws thereon, respectively, with a boot supported between said slide member and the platform, and to release the same, and consisting of a lever pivoted to said supporting frame, and accessible for operation by a person standing on said platform, and a link or links which connect said lever with said slide member.

9. The boot-jack specified in claim 1, in which the means for motivating the slide member is a lever pivoted to the supporting frame and arranged to be turned or folded into contact therewith, and which comprises locking means for securing said supporting frame and lever together in folded position.

25 10. The boot-jack specified in claim 1, in which the means for motivating the slide member is a lever pivoted to the supporting frame and arranged to be turned or folded into contact therewith, and which comprises locking means for securing said supporting frame and lever together in folded position and the platform of the boot-jack to said supporting frame.

35 11. In a boot-jack, the combination of a base section comprising a rectangular supporting frame consisting of side frame members provided with channels in their inner sides, and end members which rigidly connect said frame members in parallel, spaced relation, a platform mounted on said supporting frame comprising a block of wood or other suitable material proportioned to fit between the side members of said supporting frame with operating clearance, means for mounting said block on said frame consisting of a plate or plates secured to the under side of said block, said plate or plates being wider than said block and projecting at opposite sides thereof into engagement with the channels in the side frames and resting on the bottom sides thereof, and means for securing said platform in fixed positions on the supporting frame of said base section.

45 12. The boot-jack specified in claim 11, which also comprises a slide member, tongues or projections thereon which slidably engage the channels in the side members of the supporting frame of the base section of the boot-jack, and means operable by a person standing on the platform of the boot-jack for imparting movement to said slide member towards and from said platform.

55 13. The boot-jack specified in claim 11, in which the platform is adjustable lengthwise of the side members of the supporting frame, and which comprises a slide member, tongues or projections thereon which slidably engage the channels in the side members of the supporting frame of the base section of the boot-jack, and means operable by a person standing on the platform of the boot-jack for imparting movement to said slide member towards and from said platform.

60 14. The boot-jack specified in claim 11, in which the platform is adjustable lengthwise of the side members of the supporting frame, and which comprises a slide member, tongues or projections thereon which slidably engage the channels in the side members of the supporting frame of the base section of the boot-jack, and means

operable by a person standing on the platform of the boot-jack for imparting movement to said slide member towards and from said platform, and means for securing said platform in fixed position on the supporting frame of the base section of the boot-jack.

5 15. The boot-jack specified in claim 11, in which the platform is adjustable lengthwise of the side members of the supporting frame, and which comprises a slide member, tongues or projections thereon which slidably engage the channels in the side members of the supporting frame of the base section of the boot-jack, and means operable by a person standing on the platform of the boot-jack for imparting movement to said slide member towards and from said platform, and means for securing said platform in fixed position on the supporting frame of the base section of the boot-jack, consisting of a stud secured in the platform thereof and interchangeable in holes formed in a side member of the supporting frame of the boot-jack arranged in series lengthwise thereof.

10 16. The boot-jack specified in claim 11, in which the platform is adjustable lengthwise of the side members of the supporting frame, and which comprises a slide member, tongues or projections thereon which slidably engage the channels in the side members of the supporting frame of the base section of the boot-jack, and means operable by a person standing on the platform of the boot-jack for imparting movement to said slide member towards and from said platform, and means for securing said platform in fixed position on the supporting frame of the base section of the boot-jack, consisting of a stud secured in the platform thereof and interchangeable in holes formed in the bottom of a channel of a side member of the supporting frame of the base section, the width of said channel being proportioned to permit engagement and disengagement of said stud with and from said holes.

15 17. The boot-jack specified in claim 11, which also comprises a slide member, tongues or projections thereon which slidably engage the channels in the side members of the supporting frame of the base section, means operable by a person standing on the platform of the boot-jack for imparting movement to said slide member towards and from said platform, consisting of a lever pivoted to the supporting frame of the base member, and a link or links which pivotally connect said lever with said slide member.

20 18. The boot-jack specified in claim 11, which also comprises a slide member, tongues or projections thereon which slidably engage the channels in the side members of the supporting frame of the base section, means operable by a person standing on the platform of the boot-jack for imparting movement to said slide member towards and from said platform, consisting of a lever pivoted to the supporting frame of the base member, and a link or links which pivotally connect said lever with said slide member, said lever being substantially similar in shape, size and construction to the supporting frame of the base section of the boot-jack, and mounted thereon in such relation that it may be turned into contact with said supporting frame and will register therewith.

25 19. The boot-jack specified in claim 11, which also comprises a slide member, means for slidably mounting said slide member on the side members of the supporting frame of the boot-jack, a metal plate secured to the bottom of

- 5 said slide member, said platform and said slide member being provided in their proximate ends with openings, the sides of which converge inwardly and the bottoms of which are closed by the plates secured to the bottoms thereof, respectively, forming supports for the heel and toe portions of a boot to be removed, and forming jaws arranged to grip a boot resting on said supporting plates, and means for effecting contemplated engagement of said gripping jaws with said boot.
- 10 20. The boot-jack specified in claim 11, which also comprises a slide member, means for slidably mounting said slide member on the side members of the supporting frame of the boot-jack, a metal plate secured to the bottom of said slide member, said platform and said slide
- 15 member being provided in their proximate ends with openings, the sides of which converge inwardly and the bottoms of which are closed by the plates secured to the bottoms thereof, respectively, forming supports for the heel and toe portions of a boot to be removed, and forming jaws arranged to grip a boot resting on said supporting plates, and means for effecting contemplated engagement of said gripping jaws with said boot, the sides of the opening in the platform being proportioned to engage the counter of the boot, and the opening in the slide member comprising an under-cut portion arranged to extend inwards over the edges of the sole of a boot inserted into contemplated engagement therewith.

FRED P. MEYER.
